To all whom it may concern:

Be it known that I, OSCAR F. My design for casings for bath tubs consists of a casing or frame of substantially rectangular form, having vertical sides and ends and oblique corners, with suitable surface ornamentation.

The accompanying drawing is a perspective view of a casing embodying my design.

The sides or the outer sides and both ends of the casing are subdivided into rectangular

spaces or panels by bars *a b*, containing ornamental tiles *c c*. The oblique corners are also divided into spaces or panels *d d*, containing tiles. The casing has ornamental legs or supports and an ornamental base *F*.

What I claim as my invention, and desire to secure by Letters Patent, is—
